UNITED STATES PATENT OFFICE.

SAMUEL A. WEBBER AND WILLIAM J. DAVIS, OF WINDFALL, INDIANA,
ASSIGNORS OF ONE-HALF TO SHERIDAN CLYDE AND CHARLES K. D.
ROSS, OF ELWOOD, INDIANA.

COIN-CONTROLLED DEVICE FOR VENDING-MACHINES.

SPECIFICATION forming part of Letters Patent No. 733,924, dated July 14, 1903.

Application filed January 17, 1903. Serial No. 139,421. (No model.)

To all whom it may concern:

Be it known that we, SAMUEL A. WEBBER and WILLIAM J. DAVIS, citizens of the United States, residing at Windfall, in the county of Tipton and State of Indiana, have invented certain new and useful Improvements in Coin-Controlled Devices for Vending-Machines, &c.; and we do hereby declare the following to be a full, clear, and exact description of the invention, such as will enable others skilled in the art to which it appertains to make and use the same.

Our invention relates to coin-controlling devices for vending-machines.

One object of our invention is to provide such a device with an improved form of coin-chute having branches through which the piece deposited in a slot is adapted to meander until it reaches a receptacle.

Another object of our invention is to provide such a device with an improved construction of pivoted detent with which a genuine coin passing through a chute comes in contact to swing the same and a push-bar having a locking member with which the detent engages to arrest the movement of the push-bar until released.

Other objects and advantages will be hereinafter made clearly apparent, reference being had to the accompanying drawings, in which—

Figure 1 is a vertical section of the front part of the casing of a vending-machine, showing our improved coin-controlling device, taken on the line 1 1 of Fig. 5. Fig. 2 is a vertical section thereof, taken on the line 2 2 of Figs. 1 and 5, showing the relative position of a push-rod. Fig. 3 is a perspective view of a push-rod. Fig. 4 is a rear perspective view of that shown in Figs. 1, 2, and 3. Fig. 5 is a horizontal section of the casing, taken on line 5 5 of Fig. 2.

In order to designate the various elements of our invention and coöperating accessories, numerals will be employed, the same numeral applying to a similar part throughout the several views.

Referring in detail to the various parts of our invention, 1 and 2 indicate, respectively,

the lower and upper parts of the front wall 50 of our casing for a vending-machine, while 3 designates portions of the side walls thereof, a suitable bottom 4 being also provided. We prefer to provide an offset at the front of the casing formed by the horizontal section 55 5, and within the casing thus or otherwise fashioned we locate the various operating devices described, shown, and claimed in our application for United States Letters Patent for improvements in vending-machines, filed 60 August 21, 1902, Serial No. 120,536, which are adapted to hold the merchandise, such as cigars or the like, and deliver one of them at each operation of pushing the push-rod inward as will be hereinafter more specifically 65 set forth.

7 indicates downwardly-converging upper channels of coin-chutes, which are provided in the receiving member 8, located upon and secured to the horizontal section 5. The receiving member 8 may, if preferred, be formed of two complementary sections fitted together so that the coin-chutes 7 will be separated by the rib-section 9, which is substantially V-shaped, as will be observed, the 75 lower end thereof terminating in contact with the circular member 10, formed of glass and properly embedded between the two halves of the member 8.

The coin-chutes 7 extend downward and 80 communicate with the throat 11 by means of the inner curved branches 12. The coin-chutes 7, however, extend somewhat in a devious way, inasmuch as they diverge or spread into channels 7^a and extend downward through the horizontal section and the central part of an inner block or body section 13 in the form of converging channels 7^b, so as to deliver the coin into engagement 85 with coin-seats 14^a on the inner ends of interposed detents 14, having weighted outer ends 14^b and pivotally mounted within chambers 15, formed in the body portion 13. The interposed detents 14 being held in position 90 by suitable pivots 16, each detent is disposed 95 so that the inner end thereof will lie in the path of the coin as it falls downward in one of the converging channels 7^b of the chutes

7, thus insuring that the weight of the coins will depress the inner ends of the detents 14 and correspondingly elevate the outer ends 14^b thereof sufficiently to raise said outer 5 ends out of engagement with the inner ends 17 of inwardly-tapered locking members 18, secured to the push-rod 6 and working through inverted keyhole-slots 19 in the body portion, and thereby permit the latter to be 10 pushed inward to operate a vending device. When a push-rod 6 has been moved outward, the outer end of the interposed detent will, being weighted, drop downward in advance of the end 17, and thereby positively lock the 15 push-rod 6 from farther inward movement until another coin is placed in the chute, and thus brought into engagement with the inner end of the detent, and thereby again overbalance and raise the outer end of the de- 20 tent out of engagement with the inner end 17 of the locking member.

It will be observed that each of the detents 14 is provided with a controlling-spring 20, which are so mounted on the back of the 25 body-section that their forwardly-projecting arms 20^a will be moved upward in suitable vertical slots 21, provided in the body portion 13, the object of said springs 20 being to hold the outer ends 14^b of the detents 14 30 in positive engagement with the inclined upper edge of the locking members 18, and thus insure that said outer ends 14^b of the interposed detents 14 will be in a position to drop downward in advance of the ends 17 of the 35 locking members 18.

The object in providing that the locking members 18 shall be inwardly tapered upon their upper edges is to impart a sufficient movement to the inner ends of the detents, 40 which will cause said ends to be depressed out of the path of the coins which have been arrested by the seats 14^a, causing said inner ends to move in the arc of a circle, and thus enable the coins to drop downward past the 45 same into the coin-conveyer chute 23 and thence to the coin-box 24.

The body portion 13, in which the coin-chutes are formed, is complemented by an outer block or body portion 25, inasmuch as 50 the chute 11 extends therethrough in an outwardly-inclined direction terminating in the aperture 11^a. It will be observed that laterally and outwardly extending branches 26 are formed in the inner block 13, so as to 55 communicate, respectively, with coin-chutes 7^a, and these chutes 26 are formed to communicate with similar chutes 27, which extend outward through the outer block 25.

The object of the several branches from the 60 coin-chutes is to prevent spurious coins from being introduced into the machine to operate it. If, for instance, a five-cent piece formed of lead is dropped into the coin-chutes 7, it will strike the glass member 10, and inasmuch as lead does not possess any great degree of 65 resiliency it will pass downward through a branch 12 into the throat 11 and thence out-

ward through the aperture 11^a, formed in the outer block 25 and in the receiving throat or hopper 28 to be dropped into the receptacle 70 29, where it may be again procured by the operator, or said receiving-throat 28 may be extended into the cash-box. If the lead piece is thus caused to take this course, it is clearly obvious that it will not have any effect upon 75 the machine, inasmuch as it does not come in contact with either of the counterpoised detents 14. If, however, a five-cent piece made of iron is dropped into either of the coin-chutes 7, it will possess sufficient resiliency 80 to cause it to be deflected by the glass member 10 into a diverging branch 7^a outside of a partition-block 30, this rebounding action of the iron piece being augmented by a magnet 31, thereby causing the iron piece to be 85 attracted by or cling to the magnet and be directed thereby into a laterally-extending branch 26 and thence outward through the corresponding chute 27, formed in the outer block 25, the iron piece being delivered into 90 the receiving-chute 23, as in the case of the lead piece. When, however, a genuine coin is dropped within either of the chutes, it will strike the glass member 10 and be deflected outward thereby, and since the magnet will 95 not possess the power to change its course it will follow the course of the proper chute and thence into engagement with the seat 14^a or the inner end of the detent 14 and overbalance and elevate the outer end 14^b of the de- 100 tent, carrying the outer end 14^b of the detent out of engagement with the inner end 17 of the locking member 18, as heretofore explained, so as to enable the push-rod 6 to be 105 operated.

It will be seen that the various details of our device may be very inexpensively and expeditiously manufactured. It will be further obvious that the spurious coins will produce no force effect upon the device whereby the 110 unlocking or releasing of the push-rod is controlled.

Having thus described our invention, the following is what we claim as new therein and desire to secure by Letters Patent:

1. A coin-controlled device for vending-machines comprising a receiving member having a coin-chute, a chamber, a vertical slot in rear of and in communication with the chamber, and an inverted keyhole-slot beneath the chamber, the push-rod having an inwardly-tapered locking member and working in the keyhole-slot beneath the chamber, a detent having its inner end projecting into the coin-chute and pivoted in the chamber with its 125 outer end extending across the path of the locking member and a controlling-spring extending through the vertical slot and bearing on the outer end of the detent as set forth.

2. A coin-controlled device for vending-ma- 130 chines comprising a receiving member having a coin-chute, a chamber, a vertical slot in rear of and in communication with the chamber, and an inverted keyhole-slot beneath the

chamber, the push-rod having an inwardly-tapered locking member and working in the keyhole-slot beneath the chamber, a detent having its inner end projecting into the coin-chute, and pivoted in the chamber with its outer end extending across the path of the locking member, and a controlling-spring extending through the vertical slot bearing on the outer end of the detent and secured to the back of the body-section, and having an arm

extending through the vertical slot and bearing upon the outer end of the detent as set forth.

In testimony whereof we affix our signatures in presence of two witnesses.

SAMUEL A. WEBBER.
WILLIAM J. DAVIS.
